TUFTING BUTTON ATTACHING DEVICE

Virgil P. Carrick and Willie W. Freedle, High Point, N. C.

Application August 11, 1955, Serial No. 527,796

5 Claims. (Cl. 45—138)

This invention relates in general to new and useful improvements in upholstering tools, and more specifically to an improved tufting button attaching device.

Tufting buttons are in the form of hollow metal shells having a fabric coating on one surface thereof. The opposite surface of the tufting button is provided with a central hole through which it is necessary to pass a ribbon retaining pin. The ribbon retaining pin is solid and is carried at one end of a tufting button ribbon. It is necessary that the pin be shoved through the hole on the rear side of the tufting button and at the present time, implements such as screwdrivers are used to force the pin in place.

It is therefore the primary object of this invention to provide an improved tufting button attaching device which is so constructed whereby a tufting ribbon retaining pin, when properly positioned with respect to a tufting button, may be quickly and easily inserted within the tufting button.

Another object of this invention is to provide an improved tufting button attaching device which includes an elongated barrel having a plunger slidably mounted therein, the barrel being provided with a slot at one end thereof for receiving an end portion of a tufting button ribbon with the retaining pin thereof disposed within the barrel in alignment with the plunger for ease of insertion in a tufting button.

A further object of this invention is to provide an improved tufting button attaching device which is in the form of a guide barrel for receiving a tufting button retaining pin and a plunger for inserting the pin, the attaching device also including a handle mounted on the barrel for ease of holding the device, and a knob on the plunger for effecting the movement of the retaining pin out of the barrel and into a tufting button.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a longitudinal sectional view through the tufting button attaching device, which is the subject of this invention, and shows a tufting button ribbon positioned relative thereto ready for insertion into a tufting button;

Figure 2 is an enlarged perspective view of that end of the attaching device in which the retaining pin is inserted and shows the details of the slot formed at that end for receiving the tufting button ribbon;

Figure 3 is an enlarged plan view showing the underside of a tufting button having the ribbon thereof attached thereto, the ribbon having an intermediate portion thereof broken away; and

Figure 4 is a transverse vertical sectional view taken substantially upon the plane indicated by the section line 4—4 of Figure 3 and shows the details of the ribbon, the

2

retaining pin and the tufting button with the retaining pin positioned in place within the tufting button.

An ordinary tufting button, such as the tufting button 10 illustrated in Figure 4, includes an outer half 12 and an inner half 14. The halves 12 and 14 are interlocked and the half 12 is covered by a suitable fabric 16. The fabric 16 is interlocked between the halves 12 and 14 to retain the fabric on the half 12.

The half 14 is provided in the central portion thereof with an opening 18 for receiving a tufting button ribbon 20. The ribbon 20 is secured to the tufting button 10 by means of a retaining pin 22 which extends transversely of the ribbon 20 at one end thereof. The pin 22 is passed through the opening 18 and retained within the tufting button 10 due to the fact that its length is greater than the diameter of the opening 18.

In order that the retaining pin 22 may be inserted through the opening 18, it is necessary that a relatively great amount of pressure be placed on the pin 22 in an endwise direction. This has heretofore been done through the use of a screwdriver or a similar tool. However, this is awkward and time consuming, as well as dangerous inasmuch as the screwdriver could slip and cut one's hand in the process.

Referring now to Figures 1 and 2 in particular, it will be seen that there is illustrated a tufting button attaching device, which is the subject of this invention, the attaching device being referred to in general by the reference numeral 24. The attaching device 24 includes an elongated barrel 26 which has one end thereof closed by an end wall 28. Positioned within the barrel 26 is a bearing sleeve 30. The bearing sleeve 30 is the same length as the barrel 26.

Slidably mounted within the bearing sleeve 26 for longitudinal reciprocatory movement is a plunger 32. The plunger 32 includes a reduced end portion 34 which extends through a central opening 36 in the end wall 28. The extreme outer end of the extension 34 is provided with a knob 38 in order that the plunger 32 may be readily reciprocated within the bearing sleeve 30.

Extending transversely of the barrel 26 and secured to opposite sides thereof adjacent the end wall 28, but in spaced relation relative thereto, is a handle 40. The handle 40 is so positioned with respect to the knob 38, that when the attaching device 24 is gripped in one's hand, the fingers of one's hand may grip around the handle 40 and the thumb or palm of one's hand may engage the rear surface of the knob 38 to actuate the plunger 32.

In order that the plunger 32 may be normally retained in a retracted position, there is provided a coil spring member 42 which is telescoped over the barrel 26 and has one end thereof in engagement with the handle 40. The opposite end of the spring member 42 engages a washer 44 carried by the extension 34 in abutment with the knob 38.

Referring now to Figure 2 in particular, it will be seen that there is provided a longitudinal, elongated slot 46 in the end of the barrel 26 remote from the end wall 28. This slot 46 opens through an open end 48 of the barrel 26 and tapers longitudinally of the barrel 26 and with the sides thereof converging at a point remote from the end 48. This point is substantially adjacent the end of the plunger 32 when it is in its retracted position. The bearing sleeve 30 is provided with a slot 50 of substantially the same configuration as the slot 46.

When it is desired to insert a retaining pin 22 through an opening 18 in a tufting button, such as the tufting button 10, the ribbon 20 is passed through these aligned slots 46 and 50 and the retaining pin 22 is positioned in the barrel 26 in longitudinal alignment with the plunger 32.

After the ribbon 20 and the retaining pin 22 have been properly positioned within the barrel 26, the attaching device 24 has the open end 48 of the barrel 26 aligned with the opening 18 in a tufting button 10. The knob 38 is then pushed towards the wall 28 and the plunger 32 is advanced through the barrel 26. Plunger 32 forces the retaining pin 22 through the opening 18 so that it may assume the position illustrated in Fig. 4. When in this position, the retaining pin 22 is prevented from being accidentally pulled through the opening 18.

While it is not a part of this invention, it is pointed out that the ribbon 20 is provided at the opposite end thereof with a fitting 52. This fitting 52 is intended for use in conjunction with a special type of needle whereby the ribbon 20 may be easily positioned to hold the tufting button 10 in place.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. A tufting button attaching device for attaching a tufting button to a ribbon by inserting a ribbon retaining pin through a small opening in a tufting button, said tufting button attaching device comprising an elongated barrel, an elongated plunger slidably disposed in said barrel, one end of said plunger extending through one end of said barrel, a push knob on said one end of said plunger, an elongated slot in said barrel at the opposite end thereof, said slot extending longitudinally of said barrel and opening through said opposite end, whereby a ribbon retaining pin may be positioned in said barrel in alignment with said plunger with an attached ribbon extending through said slot.

2. A tufting button attaching device for attaching a tufting button to a ribbon by inserting a ribbon retaining pin through a small opening in a tufting button, said tufting button attaching device comprising an elongated barrel, an elongated plunger slidably disposed in said barrel, one end of said plunger extending through one end of said barrel, a push knob on said one end of said plunger, an elongated slot in said barrel at the opposite end thereof, said slot extending longitudinally of said barrel and opening through said opposite end, whereby a ribbon retaining pin may be positioned in said barrel in alignment with said plunger with an attached ribbon extending through said slot, said plunger terminating immediately adjacent said slot.

3. A tufting button attaching device for attaching a tufting button to a ribbon by inserting a ribbon retaining pin through a small opening in a tufting button, said tufting button attaching device comprising an elongated barrel, an elongated plunger slidably disposed in said barrel, one end of said plunger extending through one end of said barrel, a push knob on said one end of said plunger, an elongated slot in said barrel at the opposite end thereof, said slot extending longitudinally of said barrel and opening through said opposite end, whereby a ribbon retaining pin may be positioned in said barrel in alignment with said plunger with an attached ribbon extending through said slot, a transverse handle on said barrel adjacent said one end of said barrel, a spring member telescoped over said one end of said barrel and bearing against said handle, an opposite end of said spring member engaging said knob to urge said plunger to a retracted position.

20 4. A tufting button attaching device for attaching a tufting button to a ribbon by inserting a ribbon retaining pin through a small opening in a tufting button, said tufting button attaching device comprising an elongated barrel, an elongated plunger slidably disposed in said barrel, one end of said plunger extending through one end of said barrel, a push knob on said one end of said plunger, an elongated slot in said barrel at the opposite end thereof, said slot extending longitudinally of said barrel and opening through said opposite end, whereby a ribbon retaining pin may be positioned in said barrel in alignment with said plunger with an attached ribbon extending through said slot, a bearing sleeve in said barrel receiving said plunger, a slot in said bearing sleeve aligned with said slot in said barrel.

25 5. A tufting button attaching device for attaching a tufting button to a ribbon by inserting a ribbon retaining pin through a small opening in a tufting button, said tufting button attaching device comprising an elongated barrel, an elongated plunger slidably disposed in said barrel, one end of said plunger extending through one end of said barrel, a push knob on said one end of said plunger, an elongated slot in said barrel at the opposite end thereof, said slot extending longitudinally of said barrel and opening through said opposite end, whereby a ribbon retaining pin may be positioned in said barrel in alignment with said plunger with an attached ribbon extending through said slot, said slot having sides converging from said opposite end of said barrel.
